COCKTAIL TABLE OR THE LIKE

Ernest Herrmann, Hillsdale, N. J., assignor to Heywood-Wakefield Company, Gardner, Mass., a corporation of Massachusetts

Application March 14, 1955, Serial No. 35,039

Term of patent 7 years

(Cl. D33—14)

Fig. 1 is a perspective view of a cocktail table showing my new design, the four sides of the table being the same in appearance,

Fig. 2 is a side elevation of the table,

Fig. 3 is a top plan view thereof on a reduced scale,

Fig. 4 is an enlarged fragmentary cross-sectional view taken on the line 4—4 of Fig. 2, and

Fig. 5 is an enlarged perspective view illustrating one of the drawer pulls in detail, the concave front thereof being stippled to indicate contrast.

I claim:

The ornamental design for a cocktail table or the like, substantially as shown and described.
